(57) **CLAIM**

The ornamental design for the wire management bag, as shown and described.

DESCRIPTION

FIG. 1 is a perspective view of a wire management bag showing our new design, the broken lines representing a table are for illustrative purposes only and form no part of the claimed design;

FIG. 2 is an end elevational view thereof, the opposite end being a mirror image;

FIG. 3 is a front elevational view thereof;

FIG. 4 is a rear elevational view thereof;

FIG. 5 is a top plan view thereof; and,

FIG. 6 is a bottom plan view thereof.
